REVERSIBLE SHINGLE

Norman P. Harshberger, Scarsdale, N. Y., assignor
to The Barrett Company, New York, N. Y., a
corporation of New Jersey

Application June 5, 1931, Serial No. 542,318

9 Claims. (Cl. 108—7)

This invention relates to a roofing element and more particularly to a reversible shingle of the interlocking type.

It is an object of my invention to provide means integral with the shingle body whereby the lower exposed edge of the exposed lap portion may be securely locked down, regardless of which edge of the shingle is exposed to the weather.

It is a further object of my invention to provide a shingle element capable of being reversed in laying yet which cooperates with adjacent shingles to provide a continuous connected lower edge in each course of shingles whereby the edge portions are prevented from warping or being blown upwardly, the appearance and efficiency of the roof being consequently maintained against the elements.

Other objects and advantages of my invention will appear from the following detailed description in which

Fig. 1 is a plan view of a preferred embodiment of my improved type of shingle;

Fig. 2 illustrates a method of cutting the shingle of Fig. 1 whereby the shingle may be cut from a single web of material without waste; and

Fig. 3 illustrates a fragment of roof laid with the shingles of my invention.

In Fig. 1 wherein a preferred embodiment of my invention is shown, reference numeral 21 indicates a main body portion of a shingle 20 of general quadrilateral shape, the body of the shingle being defined by longitudinal edges 22 and 23 and by sides 24 and 25. It will be noted that the sides 24 and 25 are of substantially equal lengths, whereas longitudinal edge 23 is of somewhat greater length than longitudinal edge 22. At the intersection of side 25 and edge 23, a projecting key portion 26 is provided, the lower side of which lies in alignment with and constitutes an extension of edge 23. The side edge of key 26 extends vertically on a line parallel to the side 25 to a point of intersection with an oblique upper edge 28, the two intersecting to form a pointed projection 27. The side 25 extends vertically from the line 28 to form with an oblique line 29, a second projection 31 which is similar in shape to the projection 27. The line 29 runs inwardly toward the body portion 21 of the shingle 20 to the line 32, which rises along a vertical plane to the longitudinal edge 22, lines 29 and 32 thus defining a recess 46.

In a similar manner a key 33, projection 34, projection 35, and a recess 47 are formed adjacent the side 24.

55 The longitudinal side 23 is provided adjacent

the key portions 26 and 33 with slits or slots 36 and 37, respectively. Slits 38 and 39 in alignment with slits 36 and 37, respectively, are provided in the upper edge 22 adjacent the respective projections 31 and 35.

In Fig. 3 I have shown by way of illustration a section of a roof laid with my improved type of shingle. The several courses of the shingles shown in the roof, i. e., courses I, II and III, are shown as being laid by separate methods to more fully describe the various methods of application to which the shingle of the present invention is adapted.

In course I, which illustrates my preferred method of laying, the shingle units 20 are laid in adjacent overlapping relation with the longitudinal edges 22 and 23 placed in alignment one with another and with the longitudinal edges 23 forming the lower exposed edge of the course. The projections 27 and 34 of one shingle are locked in the slits 36 and 37 of the adjacent shingles to form a continuous lower edge which is securely locked in place. It will be noted that with respect to course I, either shingle may overlap the other so that the position of the transverse edge of the overlapping shingle varies, depending upon which of a pair of adjacent shingles overlaps the other. Hence, the shingles may be arranged to avoid a monotonous design.

In course II, the method of laying comprises a lacing of the key portions 26 and 33 and the projections 27 and 34 with the slits 36 and 37 of adjacent shingles, the projection 27 of one shingle being locked in the slit 37 of the adjacent shingle, and the projection 34 of the adjacent shingle being locked in the slit 36 of the first shingle. This lacing of the joint between adjacent shingles provides a secure and rigid connection between the adjacent shingles which serves to hold the lower edge of the course down against the roof, thereby preventing warping and consequent leaking by the action of the elements.

In course III, I have shown still a further method by which my shingle may be laid. While the adjacent shingles are laid in adjacent overlapping relation as in courses I and II, the relatively short longitudinal edge 22 of one shingle is aligned with the relatively longer longitudinal edge 23 of the adjacent shingle, the alternate relation being continued throughout the course. Considering two shingles *a* and *b* in course III, shingle *a* is laid with the longitudinal edge 23 at the top and longitudinal edge 22 at the bottom, whereas shingle *b* is laid with the longitudinal edge 22 at the top and the longitudinal edge 23 at the bot-

tom. Shingle *b* is laid to overlap shingle *a*, the shingles being locked adjacent both the top and bottom edges. At the top joint the projection 34^a is passed under projection 35^b and locked in slit 39^b. At the bottom joint, the projection 34^b locks directly with the slit 39^a. Thus the adjacent shingles of the course are formed in a continuous strip, the individual members of which are joined at both the top and the bottom edges of the strip.

10 While I have shown a roof composed of courses laid by different methods, it is to be understood that this showing is purely by way of illustration and in practice a roof could be laid with only one 15 method of laying employed throughout or a combination of methods as desired.

10 The shingles of my invention may be composed of various materials, but they are preferably constructed from a felt or fibrous base saturated with 20 bituminous material to render it waterproof, coated with a bituminous or asphalt composition and subsequently surfaced with granular material. The fibrous base is preferably manufactured in the shape of a long, continuous web 41, shown 25 in Fig. 2 having parallel sides as indicated.

15 In order that the shingle of my invention may be cut from the web 41 without waste, a method of cutting as shown in Fig. 2 is preferably followed. Four shingles are formed at one time 30 transversely of the web, although it is to be understood that any desired number may be formed, according to the relative dimensions of the web and of the shingles. The web 41 is cut transversely on lines 42, which are interrupted by the 35 cuts forming truncated triangular sections 43 alternately positioned on opposite sides of the lines 42. It will be noted that the offset sections 43 at the ends of the web are of one-half the size of the interior sections 43. The web is slitted or 40 slotted at 44 to form a series of transversely aligned slits or slots at spaced intervals longitudinally of the web. Two series of slits 44 are provided to each transverse cut 42. The web is subsequently severed on longitudinal lines 45 to provide the 45 shingle units desired. It will be noted that by the method of cutting disclosed, the slits 36, 37, 38 and 39 of the shingles 20 are formed in transverse alignment and in adjacent relation so that one cut serves to slit two shingle units. It will also 50 be noted that the recesses 46 and 47 are complementary in size and shape to the projections 26, 27 and 33, 34 of adjacent shingles, thereby eliminating waste of material in cutting since the 55 portions which are cut to form the recesses 46 and 47 form the projections 27 and 34 of the adjacent shingles. Since the cuts 44 are preferably of slit formation, no waste of material is involved therein. It is to be further understood that the above described cutting steps need not 60 be followed in the sequence in which they have been described, but the sequence may be varied or all the cuts may be made simultaneously.

65 My shingle may be made in various colors or in one color, or the shingle may be surfaced partly with material of one color and partly with material of a second color, thus producing a pleasing, vari-colored effect when laid.

70 From the above detailed description, it is obvious that my invention is possessed of many 70 advantages.

A reversible shingle is provided which is capable of being laid by a number of methods, a securely lapped lower edge being obtained by each method.

75 The structure of the shingle, including the pro-

jections at the opposite corners of one edge and the two pairs of slits in the opposite edges, one pair being located adjacent the projections, provide a shingle which may be laid either in normal adjacent relation or in alternate reversed relation to obtain any desired color effect or the like, while providing a locked lower edge which is securely held down and protected from warping and consequent action of the elements. Where the shingles are laid in alternate reversed relation, they are locked at both the upper and lower edges with a tight joint, thereby providing a strong and rigid unitary structure possessed of highly weather resistant properties.

15 I claim:

1. An interlocking shingle having interlocking projections at the ends of one longitudinal edge and having a slit adjacent each of said projections in proximity to said longitudinal edge, the projection of one shingle being arranged to lock 20 with the slit of an adjacent shingle.

2. An interlocking shingle having the general shape of a parallelogram and having interlocking projections at opposite corners of one edge, said shingle having slits in the edge adjacent 25 said projections and slits in the opposite edge of said shingle, the projections being adapted to lock with the slits of other similarly formed shingles.

3. A plurality of individual shingles with their 30 adjacent corners interlocking to form a strip, each shingle being formed with projections at the ends of one edge thereof, slits in said edge adjacent said projections, and slits in the opposite edge in alignment with said first-mentioned 35 slits, said shingles being laid in alternate reversed relation with the projection of one shingle locking with a slit of an adjacent shingle and a projection of the adjacent shingle locking with a slit of the first mentioned shingle.

4. A plurality of individual shingles assembled 40 in strips with straight edges, projections on the opposite corners of one edge of each of said shingles, slits in said edges adjacent said projections, the projections and adjacent slits of one shingle 45 being adapted to constitute a laced joint with the non-homologous projection and adjacent slit of an adjacent shingle.

5. A quadrilateral, reversible shingle having 50 interlocking projections at the opposite corners of one longitudinal edge and recesses at the opposite corners of the opposite longitudinal edge, slits in said first longitudinal edge adjacent said projections and slits in the second longitudinal edge in alignment with said first mentioned slits and adjacent said recesses.

6. A quadrilateral shingle adapted to be laid in interlocking relation with other like shingles and having two longitudinal edges adapted to be laid alternatively to the weather, said shingle having hooked projections at the ends of one longitudinal alternative weather edge, a slit near each hooked projection leading into the longitudinal edge having hooked projections at the ends thereof, and arranged to lock with the projection of another shingle, and recesses, complementary in size and shape to the hooked projections, at the ends of the other alternative longitudinal weather edge, whereby the material removed from the recesses in the cutting of said shingles may be 65 utilized in forming said hooked projections.

7. A quadrilateral shingle, reversible so that either longitudinal edge may be exposed to the weather, having hooked projections at the opposite corners of one longitudinal alternative 75

- weather edge, a slit in the neighborhood of each projection and leading into the longitudinal edge having hooked projections at the opposite corners thereof, the projection of one shingle being arranged to lock with the slit of an adjacent shingle, and recesses at the opposite corners of the opposite longitudinal alternative weather edge complementary in size and shape to said hooked projections, whereby the material removed from the recesses in the cutting of said shingles may be utilized in forming said hooked projections.
8. An interlocking shingle having interlocking projections at the opposite corners of one longitudinal edge, recesses at the opposite corners of the opposite longitudinal edge, and slits in the latter longitudinal edge adjacent said recesses, the projections of each shingle being arranged to lock with the slits of two adjacent shingles.
9. An interlocking shingle having interlocking projections at the opposite corners of one longitudinal edge, recesses at the opposite corners of the opposite longitudinal edge, and slits in the latter longitudinal edge adjacent said recesses, said shingle being adapted to be laid in overlapping courses with similar shingles, the projections of each shingle in each course being adapted to lock with the slits of two adjacent shingles in the same course.
